No. 834,797.

PATENTED OCT. 30, 1906.

F. S. GULICK.

BOTLER.

APPLICATION FILED MAY 10, 1905

UNITED STATES PATENT OFFICE.

FRANK S. GULICK, OF PITTSBURG, PENNSYLVANIA, ASSIGNOR OF ONE-THIRD TO JULIUS J. DEBOLD AND ONE-THIRD TO JOHN B. HADLEY, OF PITTSBURG, PENNSYLVANIA.

BOILER.

No. 834,797.

Specification of Letters Patent.

Patented Oct. 30, 1906.

Application filed May 10, 1905. Serial No. 259,761.

To all whom it may concern.

Be it known that I, FRANK S. GULICK, a citizen of the United States, and a resident of Pittsburgh, in the county of Allegheny and State of Pennsylvania, have invented a new and Improved Boiler, of which the following is a full, clear, and exact description.

My invention relates to boilers, and more particularly to those adapted for domestic use and in which the source of heat consists of burners to which a combustible fluid is supplied. Its principal object is to provide effective means for applying the heat.

Reference is to be had to the accompanying drawings, forming a part of this specification, in which similar reference characters designate similar parts in both the views.

Figure 1 is a central vertical section through one embodiment of my invention. Fig. 2 is a top plan view of the burners and their connecting-pipes.

A designates a boiler having a cylindrical portion 10, preferably formed of sheet-metal, this having at its ends closures in the form of a cast-metal top 11 and a similar bottom 12. The weight of this latter element is such that it is capable of retaining a considerable amount of heat for transmission to the liquid contained within the boiler. From the top of the boiler rises an outlet-pipe 12^a and at the bottom is a draw-off cock 12^b. Below the boiler is a supporting member 13, which also conveniently serves as a casing or enclosure for a burner B, this preferably having two concentric inner and outer portions 14 and 15, respectively, which are carried by brackets 16, projecting from the member 13. Air-openings 17 are shown in the lower portion of the member 13 to supply oxygen to

the burner. In the top and bottom of the boiler are alined openings to receive a flue 18, which extends from above the center of the burners. Between the burners and boiler is a coil 19, connected at one end to the bottom of the boiler at 20. This coil is of conical form and has its lower convolution situated substantially above the outer burner 15, from which it tapers upwardly to a point near the axis of the smaller burner 14. The conical coil is continued through the flue by a spiral coil 21, situated concentrically to the

walls of said flue and terminating at a point above the top of the boiler in a liquid-supply pipe 22. This pipe extends through the flue-walls and is preferably provided with a valve 55 23 to control the flow therethrough.

From the burners 14 and 15 lead pipes 24, and into the flaring end 25 of each projects the nozzle 26 of a valved pipe 29, only one of which is shown in the drawings. The pipes 60 29 lead from the casing 30, with which is connected the pipe 31 for supplying gas or other combustible fluid to the burners. The casing 30 is connected, by means of the pipe 34, with the cylinder 35, which, with the casing 65 30, forms an automatic controlling device for regulating the supply of fuel. This controlling device, however, forms no part of the present invention. From the upper side of the cylinder 35 leads a pipe 38, which is connected with the supply-pipe 22 by a T-coupling 38^a. The lower end of the pipe 38 is connected with the lower part of the boiler by the pipe 39. By the employment of two burners and the arrangement of the coil with 70 respect thereto, as shown, an intense or gentle heat can be applied as desired. When both burners are lighted, the whole coil and the bottom of the boiler will be subjected to the action of heat, whereas when the inner or 75 smaller burner only is lighted, a gentle heat will be applied to the upper part of the coil. By this means the water can be quickly heated and maintained heated with comparatively little fuel. The thick heavy bottom 80 85 of the boiler not only serves to assist in heating the water, but also in keeping it hot.

Having thus described my invention, I claim as new and desire to secure by Letters Patent—

1. A boiler, comprising a cylindrical body having sheet-metal walls and cast-metal top and bottom, a flue extending centrally through the body and above the top thereof, a tubular support for the body, a burner in the support below the flue of the body, a conical coil above the burner and terminating in a spiral coil, extending into the flue above the top of the body, the end of the conical coil being connected with the bottom of the body, 95 and a supply-pipe extending transversely through the flue and connected with the 100

body above the bottom thereof, the spiral coil being connected with the supply-pipe within the flue.

2. A boiler, comprising a cylindrical body, 5 a flue extending centrally through the body and above the top thereof, a conical coil arranged below the bottom of the body and terminating in a spiral coil extending into the flue, the end of the conical coil being connected with the bottom of the body, and a supply-pipe extending transversely through the flue and connected with the body above the bottom thereof, the spiral coil being connected with the supply-pipe within the said flue.

3. A boiler, comprising a boiler proper, a flue extending through the boiler, a conical coil arranged below the bottom of the boiler and terminating at one end in a coil extending 20 into the flue, the other end of the conical coil being connected with the bottom of the boiler, and a supply-pipe connected with the boiler above the bottom thereof and with which the upper end of the spiral coil is connected.

4. A boiler, comprising a boiler proper having sheet-metal walls and a cast-metal bottom, a flue extending through the boiler, a source of heat below the bottom of the 30 boiler, a conical coil arranged between the source of heat and the bottom of the boiler and terminating at one end in a spiral coil extending into the flue, the other end of the conical coil being connected with the bottom 35 of the boiler, and a supply-pipe connected

with the boiler above the bottom thereof and with which the upper end of the spiral coil is connected.

5. A boiler, comprising a cylindrical body having sheet-metal walls and a cast-metal bottom, a flue extending centrally through the body, a tubular support for the body, a source of heat in the tubular support, a conical coil between the source of heat and the bottom of the body, said coil having one end connected with the bottom of the body and its other end terminating in a spiral coil extending through the flue, and a supply-pipe connected with the body above the bottom thereof and with which the upper end of the 45 spiral coil is connected.

6. A boiler, comprising a cylindrical body, a flue extending centrally through the body, a tubular support for the body, a conical coil arranged in the support below the lower end of the flue, said coil having one end connected with the bottom of the body and its other end terminating in a spiral coil extending through the flue, and a supply-pipe extending 50 transversely through the flue and con-

nected with the body above the bottom of the boiler and with which the spiral coil is connected in said flue.

In testimony whereof I have signed my name to this specification in the presence of 65 two subscribing witnesses.

FRANK S. GULICK.
